[57] CLAIM

The ornamental design for a paint roller hand grip, as shown and described.

DESCRIPTION

FIG. 1 is a perspective view of the paint roller hand grip of this invention;

FIG. 2 is a right side view, the left side being identical thereto;

FIG. 3 is a top view, the bottom being identical thereto;

FIG. 4 is a right end view; and,

FIG. 5 is a left end view.

The partial broken line showing of a handle rod in FIG. 1 is for illustrative purposes only and forms no part of the claimed design.
